(57) **CLAIM**

The ornamental design for a lamp stand, as shown and described.

DESCRIPTION

A portion of this disclosure contains material to which a claim for copyright is made. The inventors or their assignee (copyright owner) have no objection to the facsimile reproduction by anyone of the patent document or the patent disclosure, as it appears in the Patent and Trademark Office files or records, but reserve all other copyright rights whatsoever.

FIG. 1 is a top, front isometric view of a first embodiment of a lamp stand showing our new design in the environment in which it is typically used.

FIG. 2 is an enlarged top, front isometric view of a lamp stand.

FIG. 3 is an enlarged front elevational view thereof.

FIG. 4 is an enlarged rear elevational view thereof.

FIG. 5 is an enlarged right side elevational view thereof.

FIG. 6 is an enlarged left side elevational view thereof.

FIG. 7 is an enlarged top plan view thereof; and,

FIG. 8 is an enlarged bottom plan view thereof.

The broken lines in the figures are for illustrative purposes only and form no part of the claimed design.
